JOSEPH KENNEDY, OF NEW YORK, N. Y.

CONCRETE INSERT.

1,045,562.

Specification of Letters Patent. Patented Nov. 26, 1912.

Application filed December 28, 1911. Serial No. 668,300.

To all whom it may concern:

Be it known that I, JOSEPH KENNEDY, a citizen of the United States, and a resident of the borough of Manhattan, city, county, 5 and State of New York, have invented certain new and useful Improvements in Concrete Inserts, of which the following is a specification, accompanied by drawings.

This invention relates to inserts for concrete and other cementitious material, adapted to be fastened to the form or mold into which the concrete is poured, and thus become embedded in the material, so that the insert remains after the mold boards are 15 removed, and forms a socket or fastening in the concrete for attaching various objects.

The objects of the invention are to improve upon, simplify, and cheapen the cost 20 of manufacture of such concrete inserts, enable the insert to be suitably fastened or centered in position in the mold preparatory to pouring and provide means for securely anchoring the device in the concrete.

25 Another object is to afford means for centering a bolt adapted to coöperate with the insert and direct the bolt so that it will more readily engage the thread on the interior of the insert.

30 Further objects of the invention will hereinafter appear, and the invention is shown in one of its preferred forms in the accompanying drawings, in which—

Figure 1 is a perspective view of an insert 35 embodying the invention; and Fig. 2 is a longitudinal sectional view showing the insert in position in a form or mold.

Referring to the drawings, A represents an insert embodying the invention adapted 40 to be embedded in the cementitious material B formed in the mold C. The insert comprises the shell D, preferably cylindrical as shown, and preferably closed at one end E, by forming the inclosing portion of the shell 45 integral with the body of the shell, or by inserting a plug, indicated by the dotted lines. The shell D may be cast, preferably in one piece otherwise suitably formed, and is interiorly threaded at F for a portion of its 50 length, in this instance the threaded portion being shown substantially midway of the length of the bore in the single thicker main body portion, for convenience of illustration, the remaining thinner integral end 55 or throat portions G and H of the bore being smooth and preferably of greater di-

ameter than the threaded portion. The walls of both the main body portion and end portions of the shell are preferably of substantially uniform exterior diameter. It 60 has been found that a practical advantage is obtained in the construction of the device by leaving the front portion G of the bore unthreaded, because the open throat so formed, which should be elongated and of 65 substantial depth as compared with the length of the central threaded portion of the shell affords means for centering a bolt as it is thrust into the insert, and directs the bolt so that it will more readily engage the 70 thread F.

The blank or smooth space or spaces G and H in the shell which are preferably of substantially the same diameter, also afford certain manufacturing advantages. If the 75 insert is made from a casting, the enlarged core has a tendency to make that portion of the casting which is to be threaded free from blow holes, and in tapping that portion which is to be threaded, a taper tap may go 80 through said portion, without requiring a second or bottoming tap to follow.

The exterior of the shell D is provided with anchoring projections which may be in the form of corrugations J which engage 85 the concrete and anchor the insert securely in place. Means are also provided on the exterior of the shell for centering and fastening the insert in position in the mold, preparatory to pouring the concrete. In 90 this instance I have shown holding flanges K and L preferably at the ends of the shell, and provided with apertures or notches O forming jaws for the reception of suitable screws or nails P by means of which the insert is held with the open end against a mold board or other support. The flanges 95 may be of any suitable shape, and the flanges L at the rear or closed end of the shell may be rectangular and there may be several 100 flanges at this point, if desired. The flange K at the front or open end of the shell is independent of the anchoring projections J and may be rounded and preferably formed at an angle to the axis of the shell, in this 105 instance said flange being bent upwardly away from the open end of the shell and terminates below the plane of the lowermost anchoring projection, so that the flange is 110 cut off contact with the mold and surface of the concrete wall, except at the base R of the shell. The concrete may thus be tamped

into the spaces between the flange and the mold and cover the flange, so that after the mold boards are removed and the tips of the nails or screws cut off or bent backward, but 5 a very small portion of the flange will show, in fact, practically nothing but the ring surrounding the hole which was in contact with the mold. This construction has the further 10 advantage of more nearly insuring a tight joint between the insert and the mold owing to the narrow line of contact between the base of the insert and the mold, which prevents water from entering the insert. Either 15 end of the device may be closed, not necessarily the end at which the plurality of flanges are formed, although the construction shown is the preferred construction, since the holding flanges also aid in anchoring the insert in the concrete, and the flanges 20 at the back of the device oppose a greater resistance to pull and to torsional stress, because of the amount of cementitious material in front of and surrounding said flanges.

I claim and desire to obtain by Letters 25 Patent the following:

A concrete insert comprising a hollow cylindrical shell or casing having a single thicker main central body portion and thinner end or throat portions, one end being 30 closed, the open end of the shell being adapt-

ed to bear flush against a mold board or other support, the walls of both the main body portion and the end portions being of substantially uniform exterior diameter, circumferential anchoring projections on the 35 exterior of the shell, the central body portion of the shell having a single interior threaded area to receive a fastening device, the end or throat portions of the shell being formed integral with the central body portion 40 and having smooth cylindrical bores of substantially the same interior diameter, but each of larger interior diameter than that of the threaded portion, the smooth bored end portion at the open end of the shell being 45 elongated and of substantial depth as compared with the length of the central threaded portion of the shell and forming a smooth throat for guiding the fastening device into the said threaded portion, and means independent of the interior threaded portion of the shell for securing the insert in position 50 against said mold board or other support.

In testimony whereof I have signed this specification in the presence of two subscribing witnesses.

JOSEPH KENNEDY.
